GRINDING MACHINE

Carl G. Flygare, Worcester, Mass., assignor to
 Norton Company, Worcester, Mass., a corpora-
 tion of Massachusetts

Application October 19, 1935, Serial No. 45,769

10 Claims. (Cl. 51—105)

This invention relates to grinding machines, and more particularly to a driving mechanism therefor.

One object of this invention is to provide a simple and thoroughly practicable driving mechanism for a grinding machine. Another object of this invention is to provide a readily removable grinding wheel assembly. Another object is to provide a driving mechanism for synchronizing the rotation of the grinding wheel and the work piece to be ground. A further object of this invention is to provide a synchronous driving connection between the grinding wheel and a truing apparatus therefor.

Another object of this invention is to provide a grinding machine driving mechanism in which the rotation of the grinding wheel, the rotation of the work piece, and the movement of the truing tool are all synchronized. Another object of this invention is to provide such a driving mechanism with readily detachable connections which permit ready removal of the grinding wheel assembly for changing the grinding wheel when desired. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a fragmentary plan view of a grinding machine embodying this invention, having parts broken away and shown in section to more clearly show the construction;

Fig. 2 is a left-hand elevation of the machine as shown in Fig. 1;

Fig. 3 is a sectional view taken approximately on the line 3—3 of Fig. 2, showing the synchronized drive between the wheel spindle and the work piece;

Fig. 4 is a fragmentary sectional view, on an enlarged scale, taken approximately on the line 4—4 of Fig. 2;

Fig. 5 is a fragmentary sectional view, on an enlarged scale, taken approximately on the line 5—5 of Fig. 4;

Fig. 6 is a fragmentary sectional view, on an enlarged scale, of the adjustment for the driving gear, taken approximately on the line 6—6 of Fig. 5;

Fig. 7 is a fragmentary detail view, on an en-

larged scale, of the backlash eliminating device in the gear drive;

Fig. 8 is a fragmentary front elevation of the end of the casing for the transverse drive shaft, as shown in Fig. 3;

Fig. 9 is a fragmentary cross-sectional view, taken approximately on the line 9—9 of Fig. 1, showing the operation of the grinding wheel truing mechanism;

Fig. 10 is a fragmentary longitudinal section, on an enlarged scale, taken approximately on the line 10—10 of Fig. 1;

Fig. 11 is a fragmentary end elevation of a portion of the work driving head, showing the work rotation brake;

Fig. 12 is a fragmentary elevation, on an enlarged scale, of the work driving head; and

Fig. 13 is a fragmentary view having parts broken away and cross-sectioned to show the work feeding mechanism.

The embodiment of this invention selected for illustration comprises a grinding machine having a base 10 which supports a transversely movable carriage 11 on the ways 12, 13 and 14. The carriage 11 in turn supports a longitudinally movable work supporting table 15 which is mounted to slide longitudinally thereon on V-way 16 and flat way 17. The table 15 supports a headstock 18 and footstock 19 which serve as a rotatable support for a work piece, such as a camshaft 20.

The base 10 is arranged to rotatably support a grinding wheel spindle 25 in suitable bearings 26 and 27. The wheel spindle 25 is provided with a wheel support which is arranged to support a plurality of grinding wheels 28 which in the form illustrated are non-circular in shape.

The grinding machine shown in this embodiment of the invention is particularly applicable to the type of machine shown in the prior patent to Stubbs No. 1,958,551 dated May 15, 1934, in which a work piece of non-cylindrical shape is ground while mounted on centers by means of a plurality of grinding wheels, the peripheries of which are formed the conjugate in shape to that of the shape desired to be produced on the finished ground work piece.

The carriage 11 is arranged to be moved transversely relative to the grinding wheels 28 to feed the work piece 20 toward and from the peripheries of the wheels by means of a feeding mechanism, such as for example that shown in the prior U. S. patent to Wood No. 1,969,997 dated August 14, 1934. This mechanism may comprise a nut and screw feed mechanism including a nut 30 depending from the slide 11. The nut 30 meshes

with a rotatable feed screw 31 which may be rotated through a gear mechanism by a manually operable feed wheel 32. The details of this feed mechanism have not been fully illustrated 5 since this mechanism is not considered part of the present invention. For further details of this mechanism, reference may be had to the prior patent to Wood above mentioned.

In a massive machine of this type, where the 10 wheel spindle 25 is supported at its opposite ends by the bearings 26 and 27, it is desirable to provide a readily accessible means for removing the wheel assembly to permit changing the grinding wheels when they become worn away. In the 15 preferred form, the bearings at the opposite ends of the spindle 25 are supported in the cylindrically shaped casing members 35 and 36. The base 10 is provided with a pair of opposed semi-cylindrical surfaces 37 and 38 which support the 20 bearing casings 35 and 36, and a pair of readily removable bearing caps 39 and 40 serve to hold the bearing casings 35 and 36 in adjusted position on the base 10 by means of bolts 41. The wheel spindle 25 is provided with reduced end 25 portions 42 (only one of which is shown), and a pair of anti-friction bearings 45 and 46 are interposed between the reduced portion 42 of spindle 25 and the cylindrical bearing casing 35. This bearing construction is duplicated within the 30 bearing casing 36. Only one of the bearings is shown in section to illustrate the construction. It will be readily apparent from the foregoing disclosure that when it is desired to remove the wheel assembly for changing the grinding wheel, 35 the bolts 41 and the bearing caps 39 and 40 are removed and the entire grinding wheel spindle assembly including the bearing casings 35 and 36 may be then readily lifted from the machine. The outside diameter of the bearing casings 35 40 and 36 is of such a size that the grinding wheel annulus may be readily slid axially from the assembly when they are changed. The wheel spindle 25 may be driven by means of a pulley 47 from any suitable source of power.

45 In order that the grinding wheels 28 may be trued to the proper shape so that they are the conjugate of the work piece to be ground, a truing apparatus is provided comprising the transversely movable slide 50 which is arranged to be moved 50 transversely on ways 51 of the base 10 by means of a feeding mechanism including a nut 52 carried by the slide 50. The nut 52 engages a feed screw 53 which is carried by the base 10 and is arranged to be rotated by a hand wheel 54.

55 The transversely movable slide 50 carries a longitudinally movable slide 58 mounted to slide longitudinally on ways 59 on the transversely movable slide 50. The slide 58 is arranged to be moved longitudinally on the carriage 58 by means 60 of a hand wheel 60 which is supported on the outer end of a feed screw 61 which in turn meshes with a nut 62 which is carried by the longitudinally movable slide 58.

The slide 58 supports a plurality of transversely movable truing tool slides 64, 65, 66 and 67, each of which is arranged to slide on slideways 68 within the slide 58. There is a truing tool for each slide arranged opposite to each of the grinding wheels of the assembly.

70 In order that the truing tools may true the peripheries of the wheels to a shape that is the conjugate of the work to be ground, a rotatable camshaft 69 carries a plurality of master cams 70, 71, 72 and 73, each of which is arranged to engage 75 a follower surface 74 on its corresponding slide 64,

65, 66 and 67. One of the slide constructions is illustrated in detail, as shown in Fig. 9. A pair of springs 75 and 76 is interposed between each of the truing tool slides and the slide 58 which normally hold the truing tool slides 64, 65, 66 and 67 in a forward position so that a follower surface 74 on each of the slides engages the corresponding cam 70, 71, 72 and 73. The master camshaft 69 is rotated and this rotation serves to rotate the master cams to cause a transverse movement of the truing tool slides 64, 65, 66 and 67 so that the truing tools will generate a predetermined shape which is the conjugate of the work piece to be ground. The master camshaft 69 is rotatably supported in bearings 77, 78 and 79 in the slide 58 15 so that any rotation of the shaft 69 serves to cause a rotation of the master cams 70, 71, 72 and 73 to move the truing tool slides 64, 65, 66 and 67, in accordance with the shape or contour of the master cams, to produce the desired shape upon 20 the periphery of the grinding wheel.

In order that the non-circular grinding wheel 28 may produce a conjugate shape upon the periphery of the work piece being ground, it is necessary to synchronize the rotation of the 25 grinding wheel with the rotatable work support, and it is further necessary to synchronize the rotation of the master cams on the truing apparatus with the rotation of the grinding wheel, as well as the rotation of the work, in order that 30 the grinding wheels may be trued to a proper shape or contour to produce the work of the desired shape. In the embodiment illustrated, the rotative power of the wheel spindle 25 is transmitted through a gear mechanism to rotate a 35 transverse shaft which is connected through gearing to rotate both the work piece and the master camshaft of the truing mechanism. A gear casing 80 is mounted on a projecting boss 81 of the bearing casing 35 and is fixed thereto by means of 40 screws so that the spindle bearing casing 35 and the gear casing form an integral unit.

A reduced portion 82 of the spindle 25 carries a bevel gear 83 which is keyed thereto by means of a key 84. The gear 83 meshes with a bevel 45 gear 85 which is connected by a key 86 with a rotatable sleeve 87 supported in bearings 88 and 89 in gear casing 80.

A gear casing 90 is mounted on the transversely movable table 11. The gear casing 90 carries a 50 rotatable sleeve 91 which is supported in bearings 92 and 93. The sleeve 91 carries a bevel gear 94 which meshes with a bevel gear 95 which is keyed to a rotatable sleeve 96 journaled in the gear casing 90.

The sleeve 96 is operatively connected to rotate a headstock sleeve 97 which is rotatably mounted within headstock 18. The headstock 18 is mounted on the longitudinally movable table 15 and the gear casing 90 is supported on the transversely movable slide 11 so that it is necessary to provide a sliding driving connection between the sleeve 96 and the sleeve 97. In the embodiment illustrated, a substantially triangularly shaped splined shaft 98 is utilized. This splined shaft 65 is preferably made in accordance with the U. S. patent to Stubbs No. 1,912,412 dated June 6, 1933. The splined shaft 98 is connected to the sleeve 97 by means of a collar 99 within an aperture 100. The other end of the shaft 98 is slidably mounted in an aperture 101 in the sleeve 96 which is shaped to fit the shaft 98 so as to permit a longitudinal movement of the headstock 18 relative to the gear casing 90.

The rotation of the headstock sleeve 97 and the 75

wheel spindle 25 are synchronized by connecting the rotatable sleeve 87 in the gear casing 80 with the rotatable sleeve 91 in the gear casing 90 by means of a splined shaft 102. The shaft 102 is held within an aperture 103 in sleeve 91 by means of a rod 104 having a head 105 engaging a cover plate 106 at the end of sleeve 91. A spring 107 surrounds the rod 104 and is interposed between the end cap 106 and the shaft 102 and serves to hold the shaft in its normal driving position. The other end of the shaft 102 fits within an aperture 108 within the sleeve 87 and is arranged to slide within said aperture so as to permit a driving connection between the wheel spindle 25 and the headstock sleeve 97 during the transverse movement of the slide 11.

It is desirable to provide a readily detachable driving connection between the gear box 80 and gear box 90 so that the driving connection may be readily disconnected when it is desired to remove the grinding wheel assembly from the machine. This is preferably accomplished by sliding the shaft 102 endwise toward the front of the machine. The end of the gear casing 90 is provided with a cover plate 110 which is pivotally connected thereto by means of a screw 111. The cover plate is swung to a position so as to allow the shaft 102 to be withdrawn until the collar 105 projects beyond the cover plate 110. The cover plate 110 is then swung into position 110a so that the notch 112 engages the rod 104 behind the collar 105. The operator may then turn the wheel 32 to move the transversely movable slide 11 toward the left, as viewed in Fig. 13, through a sufficient distance to withdraw the shaft 102 from the aperture 108 in sleeve 87, thereby disconnecting the driving connection between the gear box 80 and the gear box 90 so as to permit the wheel spindle assembly to be readily removed from the machine.

In order that the rotation of the master cam-shaft 69 may be synchronized with the rotation of the grinding wheel spindle 25 and also with the rotation of the work piece 20, a gear box 115 is mounted on the transversely movable slide 50. The camshaft 69 has a reduced end portion which is formed as a splined shaft 116 arranged to slide within a central mating aperture in the rotatable sleeve 117 in gear casing 50 115. A bevel gear 118 is keyed to the sleeve 117 and meshes with a bevel gear 119 which is carried by a rotatable sleeve 120 journaled within gear casing 115.

A shaft 121 serves to connect the sleeve 120 with the sleeve 87 in gear box 80 so as to transmit a rotary motion through bevel gears 119 and 118 to rotate the master camshaft 69 in synchronism with the wheel spindle 25. The shaft 121 is formed as a triangular splined shaft, as above described, and as illustrated in Fig. 5, having a portion slidably engaging a correspondingly shaped aperture 108 in the sleeve 87 and the other end portion of the shaft 121 is slidably mounted within a correspondingly shaped aperture 122 in the sleeve 120.

The shaft 121 is held in driving engagement with the sleeve 87 during the transverse movement of the truing tool slide 50 by means of a spring 124 which is interposed between the end 70 of sleeve 120 and a collar 125 on the shaft 121. The end of the gear casing 115 is provided with a cover plate 126 which is formed identical with the cover plate shown in Fig. 8. When it is desired to disconnect the driving connections between gear boxes 80 and 115, the cover plate

126 is swung on pivot screw 127 to open the central aperture and the shaft 121 is moved rearwardly against the tension of the spring 124. The cover plate is then swung into position to engage a reduced portion 128 on the shaft 121 so as to lock the shaft in its rearward position. The operator may then manually turn the feed wheel 54 to move the truing apparatus slide 50 rearwardly so as to carry the gear box 115 and shaft 121 rearwardly until the shaft 121 disengages the sleeve 87 so as to permit ready removal of the gear box 80 with the grinding wheel assembly for changing of wheels.

In order that the sleeve 87 in gear box 80 may be readily aligned with shafts 102 and 121 when the grinding wheel assembly is removed and replaced, the gear box 80 is provided with a depending plate 130 having a locating surface 131 arranged to engage a locating bar 132 on the base 10. When the grinding wheel assembly is inserted in the machine, the bearing casings 35 and 36 are lowered into their mating surfaces 37 and 38 and the locating surface 131 of plate 130 engages the bar 132 and locates the gear casing 80 so that the rotatable sleeve 87 supported there-in is aligned with the shafts 102 and 121.

In order that the grinding wheels, the work piece and the master cam for actuating the truing tools may be rotated in absolute synchronism with each other, it is desirable to provide a backlash eliminating mechanism in the gear drive. Each of the gear drives contained in the gear box 80, gear box 90, and gear box 115 is provided with suitable means to eliminate any backlash so that the driven shafts are rotated in absolute synchronism with the grinding wheel spindle 25. A bevel gear 135 is keyed to the bevel gear 83 and meshes with a bevel gear 136 which is rotatably mounted on a hub 137 of the gear 85. A yieldable connection, such as a spring 138, is provided between the gear 136 and the gear 85 to eliminate any backlash between the gears. The spring 138 is preferably of a helical type having one of its ends connected to gear 85 and its other end connected to the gear 136. When the gears 85 and 136 are assembled, the spring 138 is put under tension by rotating the gear 136 relative to the gear 85 and a pin 134 projecting from the gear 85 engages a slot in the hub of the gear 136 to hold the two gears with the spring 138 under tension while the assembly of the unit is completed. The slot in the hub of the gear 136 is wider than the pin 134, thus permitting a relative motion between the gears 136 and 85, so that the tension of the spring 138 serves at all times, after the gears are meshed with the driving gears 83 and 135, to eliminate the backlash therebetween.

Similarly, each one of the gear sets is provided with a pin 134 which serves to lock the bevel gears with the backlash elimination spring under the desired tension before assembly of the individual gear units.

The gear box 90 is provided with a backlash eliminator including a bevel gear 139 which is keyed to gear 94 and meshes with a gear 140 rotatably mounted on a hub of gear 95. A spring 141 serves to yieldably connect the gear 140 with the gear 95 to eliminate any backlash between the shaft 102 and the shaft 93.

The gear box 115 is provided with a similar backlash eliminator comprising a bevel gear 143 which is keyed to gear 119 by means of a bearing sleeve 149 for both gears and meshes with a bevel gear 144 which is rotatably mounted on a

hub of gear 118. A spring 145 serves to yieldably connect the gear 144 with the gear 118 to eliminate any backlash in the driving connections between shafts 121 and the master camshaft 69.

- 5 It is necessary to time the shaft 69 relative to the wheel spindle 25 and also to time the work rotation with the wheel spindle 25. These shafts may be roughly timed in assembly by positioning the bevel gears in the gear boxes 80, 90 and 115.
  - 10 It is desirable, however, to provide a suitable adjusting mechanism so that the timing of the work piece 20 and the timing of the master camshaft 69 of the truing mechanism may be readily adjusted. This is preferably accomplished by providing an angular adjustment for the driving gears 94 and 119. Details of this adjustment for the gear 119 have been illustrated in Figs. 4, 5 and 6. The sleeve 120 is formed with an integral flange 148, and gear 119 is rotatably mounted on a sleeve 149. The gear 119 is locked to the flange 148 by means of screws 151 and 152 which pass through elongated slots 153 and 154 in the flange 148 and are screw threaded into the gear 119. By tightening the screws 151 and 152, the gear 119 may be locked into driving relation with the flange 148.

In order to facilitate angular adjustment between the gear 119 and flange 148, a pair of diametrically opposed screws 155 and 156 are provided. These screws are screw threaded into the gear 119 and are each provided with enlarged heads having a frusto-conical surface 157 which is arranged to engage the frusto-conical surfaces 159 and 160 in the flange 148. By loosening the screws 151 and 152 and then manipulating the adjusting screws 155 and 156, the gear 119 may be adjusted relative to the flange 148 so as to accurately time the rotation of the shaft 69 relative to the wheel spindle 25.

40 A similar adjusting mechanism is provided for timing the gear 94 relative to the shaft 102 and the work head spindle 97. This mechanism is identical with that above described and consequently has not been illustrated in detail. A pair
45 of opposed clamping screws 163 pass through elongated slots in the flange 164 and are provided to clamp the gear 94 to the flange 164 which is formed integrally with the sleeve 91. A pair of diametrically opposed adjusting screws
50 165 and 166 serve to adjust the position of the gear 94 relative to the flange 164. After the gear has been adjusted, the flange and the gear are locked by means of the clamping screw 163 so that the rotation of the headstock spindle 97 is
55 accurately timed with the wheel spindle 25 and also with the master camshaft 69 of the wheel truing apparatus 58.

The camshaft to be ground is rotatably supported between the headstock 18 and footstock 19 on a headstock center 175 and a footstock center 176. The footstock may be of any of the well known constructions, such as that shown in the expired patent to Norton No. 762,838 dated June 14, 1904, in which the footstock center 176 is adjusted relative to the work piece by means of a hand wheel 177. The headstock drive for the work is preferably arranged so that the work may be removed from the machine without stopping the rotation of the headstock spindle 97. A sleeve 179 is slidably mounted within the headstock spindle 97. The sleeve 179 carries a rotatable work driving head 180 which is screw threaded onto the end of the sleeve 179. The work driving head 180 is connected by means of a slot to a single tooth clutch 181 on the head-

stock spindle sleeve 97. A brake member 182 is carried by the head 180 and in the normal operation of the machine during grinding is inoperative and rides within an aperture 183 within the casing 184. The member 182 is provided with a brake ring 185 which is arranged to engage a braking surface 186 on the casing 184. A spring 187 within the headstock sleeve 97 acts upon the head 188 of a plunger 189 and serves to exert a pressure tending to move the sleeve 179 toward the right, so as to maintain the center 175 in supporting engagement with the work piece 20, as viewed in Fig. 3. When the work is removed from the machine, the operator turns the footstock wheel 177 to withdraw the footstock center 176, and the released tension of the spring 187 serves to move the sleeve 179 and the head 180 toward the right, as viewed in Fig. 3, so that the single tooth clutch 181 is disengaged, thereby disconnecting the drive to the head 180. The brake shoe 185 engages the braking surface 186 and thereby stops the rotation of the head 180 and work piece 20. The hand wheel 177 on the footstock 19 is then rotated further to withdraw the footstock center 176 from engagement with the work, and the work piece may then be readily removed from operating position on the machine. The head 180 is preferably formed in two parts comprising a work driving member 190 having a dog tooth 191 which is arranged to engage a notch in the end of the work piece. The head 180 is provided with a lug 192 carrying an adjusting screw 193 which is arranged to abut against a plate 194 of the driving member 190 so that the plate 194 may be adjusted by means of the screw 193 relative to the head 180 to permit a further timing adjustment of the work piece relative to the rotation of the headstock sleeve 97 and the wheel spindle 25. The plate 194 may be locked in adjusted position by means of the clamping bolts 195 and 196 which are screw threaded into the head 180 and pass through elongated slots 197 and 198 in the plate 194.

In the operation of this machine, the wheel spindle assembly is mounted in place with the bearing casings 35 and 36 supported on their bearing surfaces 37 and 38. The bearing caps 39 and 40 are then clamped in position by means of the screws 41. The aligning surface 131 engages the positioning lug 132 which is preferably formed integral with the base 10 and thereby aligns the rotatable sleeve 87 in the gear box 88. The driven shafts 102 and 121 are then slid into driving engagement with the sleeve 87 and the master camshaft 69 is then timed in the proper relation with the wheel spindle by manipulation of the adjusting screws 155 and 156. The headstock spindle 97 is then timed in the desired relationship with the wheel spindle 25 by adjustment of the screws 165 and 166. The wheel spindle is then started in rotation and the grinding wheels are trued by turning the feed wheel 54 to move the slide 50 toward the grinding wheels, and wheel 60 is rotated to traverse the truing tools across the peripheries of the grinding wheels so as to generate the predetermined contour on the periphery of the wheels which is the conjugate of the shape to be ground on the portions of the work piece. The machine is then ready for the grinding operation and the operator inserts a work piece 20 on the head and footstock centers 175 and 176, turns the footstock wheel 177 to slide the sleeve 179 within the spindle 97 to disengage the braking disk 185 from the surface 186 and thereby start the work rotation. The work

table carriage 11 may then be moved transversely by turning the feed mechanism to feed the work piece toward the wheel axis to simultaneously grind a plurality of portions on the work piece to 5 the desired shape and size.

It will thus be seen that there has been provided by this invention apparatus in which the various objects hereinabove set forth together with many thoroughly practical advantages are 10 successfully achieved. As many possible embodiments may be made of the above invention and as many changes might be made in the embodiments above set forth, it is to be understood that all matter hereinbefore set forth, or shown 15 in the accompanying drawings, is to be interpreted as illustrative and not in a limiting sense.

I claim:

1. A grinding machine comprising a base, a rotatable grinding wheel, a wheel spindle to support said wheel, spaced bearing assemblies to support said spindle, said bearing assemblies having outer supporting surfaces, spaced aligned surfaces arranged to mate with and align said bearing surfaces on the base, a rotatable work 25 support, a transversely movable slide supporting one of said elements which is arranged for movement relatively toward and from the other, means to rotate the grinding wheel spindle, driving connections between the wheel spindle and the work support to synchronize the rotation thereof including gearing on the end of said wheel spindle, gearing on the end of said rotatable work support, a telescopic drive shaft between said sets of gears, said telescopic shaft being arranged so that it may be disconnected, and means to lock and hold said shaft disconnected to facilitate removal of the grinding wheel 35 spindle assembly.

2. A grinding machine comprising a base, a 40 rotatable grinding wheel, a wheel spindle to support said wheel, a pair of spaced bearings for said spindle on opposite sides of said wheel, casings to support said bearings having outer supporting and aligning surfaces, aligned spaced 45 supporting surfaces for said bearing assemblies, a truing apparatus including a truing tool, means to cause said truing tool to move longitudinally and transversely relative to the operative face of the grinding wheel, means including a rotatable cam and a drive shaft therefor to move the truing tool toward and from the operative face 50 of the grinding wheel, disconnectable driving connections including a telescopic drive shaft between the grinding wheel spindle and the cam-shaft to synchronize the rotation of the grinding wheel and the truing tool cam so as to facilitate removal of the grinding wheel, and means to lock and hold said shaft disconnected to facilitate removal of the wheel assembly.

3. A grinding machine comprising a base, a 60 rotatable grinding wheel, a wheel spindle which is rotatably supported on said base, a truing tool, means including a rotatable cam to cause said truing tool to move toward and from the operative face of the grinding wheel to true the same, means to synchronize the rotation of the wheel spindle and the cam-shaft including a transversely extending telescopic shaft, gearing connecting the wheel spindle and said transverse shaft, means to take up backlash in said gearing, driven 65 gearing connecting the other end of said transverse shaft and the cam-shaft, and means to take up backlash in said gearing so as to rotate the 70 cam in synchronism with the grinding wheel so

as to generate a predetermined contour on the wheel periphery.

4. A grinding machine comprising a base, a rotatable grinding wheel, a wheel spindle which is rotatably supported on said base, a truing tool, means including a rotatable cam to cause the truing tool to move toward and from the operative face of the wheel to true the same, means to synchronize the rotation of said wheel spindle and cam-shaft including a transversely extending 10 telescopic shaft, anti-backlash gearing connecting said wheel spindle and said transverse shaft, driven anti-backlash gearing connecting the other end of said transverse shaft and the cam-shaft to rotate the cam in synchronism with the 15 grinding wheel so as to generate a predetermined contour on the wheel periphery, yieldable means to hold said telescopic shaft in a driving position, and means to withdraw and hold said telescopic shaft disconnected from the wheel spindle to facilitate removal of the grinding wheel assembly.

5. A grinding machine comprising a base, a rotatable grinding wheel, a wheel spindle to support said wheel, bearings for said spindle, a rotatable work support including a rotatable headstock spindle, means to move the grinding wheel and the work support transversely and relatively toward and from each other, and means to rotate said headstock spindle in synchronism with said grinding wheel spindle including a trans- 30 verse drive shaft, anti-backlash gear connections between the wheel spindle and the transverse shaft, gear connections between said transverse shaft and the headstock spindle, and means to adjust the timing between said grinding wheel spindle and headstock spindle so that the grinding wheel and the rotatable work piece are rotated in synchronism and in timed relation with each other.

6. A grinding machine comprising a rotatable 40 grinding assembly having a plurality of grinding wheels mounted thereon, a rotatable wheel spindle to support said assembly, spindle bearings arranged at opposite ends of said spindle and on opposite sides of said wheel assembly, removable mountings for said bearings on the base, a rotatable work support including a headstock spindle, means to relatively move said wheel assembly and work support transversely relative to each other, driving connections between the wheel spindle and headstock spindle including a transverse drive shaft, gearing connected between the wheel spindle and said transverse shaft, a gearing between the transverse shaft and headstock spindle, a telescopic transverse drive shaft which is arranged so that it may be disconnected, and means to hold said telescopic drive shaft disconnected from the wheel spindle gearing to facilitate removal of the grinding wheel assembly.

7. A grinding machine comprising a base, a rotatable grinding wheel, a spindle to support said wheel, a rotatable work support, a slide supporting one of said elements for movement toward and from the other, means to removably support the grinding wheel spindle, means to rotate said spindle, a truing apparatus including a truing tool which is arranged to be moved transversely and longitudinally relative to the operative face of the wheel, means including a cam and a drive shaft to cause the truing tool to move toward and from the periphery of the wheel to true the same to a predetermined contour, and a driving mechanism to synchronize the rotation of the work support and the cam-shaft with the 70 75

- grinding wheel spindle including gearing on one end of said wheel spindle, gearing on the end of said rotatable work holder which is aligned with the gearing on the wheel spindle, gearing 5 on the end of said camshaft which is aligned with the gearing on the wheel spindle, and a pair of telescopic driving shafts connecting the gearing on the wheel spindle with the gearing to rotate the work support and the gearing 10 to rotate the truing tool cam.
8. A grinding machine comprising a base, a rotatable grinding wheel, a spindle to support said wheel, a rotatable work support, a slide supporting one of said elements for movement 15 toward and from the other, means to removably support the grinding wheel spindle, means to rotate said spindle, a truing apparatus including a truing tool which is arranged to be moved transversely and longitudinally relative to the 20 operative face of the wheel, means including a cam and a drive shaft to cause the truing tool to move toward and from the periphery of the wheel to true the same to a predetermined contour, and a driving mechanism to synchronize the 25 rotation of the work support and the camshaft with the grinding wheel spindle including gearing on one end of said wheel spindle, gearing on the end of said rotatable work holder which is aligned with the gearing on the wheel spindle, gearing 30 on the end of said camshaft which is aligned with the gearing on the wheel spindle, a pair of aligned spaced telescopic drive shafts connecting the gearing on the rotary work support with the gearing on the wheel spindle and connecting the 35 gearing on the camshaft with the gearing on the wheel spindle, and means to telescope and hold said shafts within the respective gear mechanisms to disconnect the work support from the wheel spindle and to disconnect the cam from the 40 wheel spindle drive to facilitate removal of the grinding wheel assembly.
9. A grinding machine comprising a base, a rotatable grinding wheel, a wheel spindle to sup-

port said wheel, a work supporting table, means to move said table and wheel spindle relatively toward and from each other, a headstock and footstock mounted on said table, a continuously rotated spindle on said headstock, means to rotate said wheel spindle, driving connections between the wheel spindle and headstock spindle to synchronize the rotation thereof, a work supporting and driving head associated with said spindle which rotates with the headstock spindle 10 during the grinding operation, a brake associated with said work driving head, and a single tooth clutch between the work driving head and the headstock spindle which is arranged so that when the work piece is mounted on centers and 15 the footstock is adjusted into an operating position the work driver is moved axially to release the brake and engage the clutch to start the rotation of the work.

10. A grinding machine comprising a base, a 20 rotatable grinding wheel, a wheel spindle to support said wheel, a work table, means to cause a relative transverse feeding movement between the work table and wheel spindle, a headstock and footstock on said table, a headstock spindle, 25 synchronous driving connections between the wheel spindle and headstock spindle to continuously rotate the headstock spindle, a work supporting and driving head associated with said spindle which rotates with the headstock spindle 30 during the grinding operation, a brake associated with said work head, a single tooth clutch between the work drive head and the headstock spindle which is arranged so that when the work piece is mounted on centers and the foot- 35 stock is adjusted into an operating position the work driver is moved axially to release the brake and engage the clutch to start the rotation of the work and a locating device on said head to locate the work piece in a predetermined rotary 40 position with respect to said wheel spindle and headstock spindle.
